Eduard R. Huegel, Brooklyn, N. Y., assignor to
Rambusch Decorating Company, New York,
N. Y., a corporation of New York

Application April 1, 1952, Serial No. 19,144

Term of patent 14 years

(Cl. D48—23)

To all whom it may concern:

Be it known that I, Eduard R. Huegel, a citizen of the United States of America and a resident of the Borough of Brooklyn, county of Kings, city and State of New York, have invented a new, original, and ornamental Design for a Ceiling Lighting Fixture, of which the following is a specification, reference being had to the accompanying drawing, forming a part thereof.

In this drawing:

Figure 1 is a side elevational view of a ceiling lighting fixture, showing my new design;

Figure 2 is an inverted plan view thereof; and
Figure 3 is a top plan view of the same.

I claim:

The ornamental design for a ceiling lighting fixture, as shown.

EDUARD R. HUEGEL.
